UNITED STATES PATENT OFFICE.

GEORGE FOUNTAINE WEARE HOPE, OF STANFORD LE HOPE, AND HAROLD WILLIAM JOSHUA CHEFFINS, OF SEAFORD, ENGLAND.

BALL OR PEBBLE MILL.

1,054,415.

Specification of Letters Patent. Patented Feb. 25, 1913.

Application filed June 29, 1912. Serial No. 706,662.

To all whom it may concern:

Be it known that we, GEORGE FOUNTAINE WEARE HOPE, a subject of the King of Great Britain, residing at the Bungalow, Stanford le Hope, in the county of Essex, England, and HAROLD WILLIAM JOSHUA CHEFFINS, a subject of the King of Great Britain, residing at 5 Marine Parade, Seaford, in the county of Sussex, England, have invented 5 new and useful Improvements in Ball or Pebble Mills, of which the following is a specification.

Our invention relates to improvements in ball or pebble mills or the like.

15 Our invention is applicable to that type of dry grinding mill in which a revolving cylinder is employed mounted on rollers and driven by suitable gearing, such cylinder being usually open at both ends and adapted 20 to contain the pulverizing material as well as the material to be ground. In such machines the material is usually fed to the cylinder through one of its open ends by means of a hopper while the ground material is 25 often withdrawn through the other end into a separate settling chamber by compressed air or by means of a fan.

According to our invention we arrange in the mill or the like, which is conveniently 30 in the form of a rotating cylinder mounted on rollers as above described, a stationary chamber or a series of chambers which may be arranged in an upright position on the central axis of said mill or if found desirable 35 able at any convenient angle above the center of said mill. The said stationary chamber is provided with an inlet at its upper end and an outlet leading to the hollow trunnion or stationary disk or disks at the 40 end or ends of the cylinder. The inlet of said chamber is provided with a suitably shaped hood adapted to prevent the entrance into the chamber of any large particles which may be carried to the top of the 45 mill during its rotation.

We find in practice that it is desirable to provide a convenient method of grading the consistency of the powder extracted from the mill and in order to do this we prefer 50 to arrange the extracting chamber in such a manner that the height of its inlet from the center of the mill can be adjusted. It will be obvious that when the inlet to the chamber is arranged in the highest part of the 55 mill only the finest dust will pass in through

the inlet to the collecting chamber while when the inlet of said chamber is arranged in a position nearer the level of the material in the mill the coarser dust will pass with the finest dust into said collecting chamber 60 and from said chamber through the outlet under the influence of compressed air or the suction created by the fan or by any other means.

We provide in the hollow trunnions or 65 disk or disks at the end or ends of the mill a pipe forming a compressed air inlet provided with a series of jets adapted to direct compressed air upon the balls or pebbles during the rotation of the mill in this manner preventing the powder from collecting 70 on the surface of the pebbles and thus causing cushioned surfaces thereon which destroy their grinding efficiency.

Our invention is illustrated by way of 75 example in the accompanying drawings in which—Figure 1. shows a side view partly in section of the mill. Fig. 2. shows a section on the line A—B of Fig. 1. Fig. 3. shews an alternative form of our invention 80 in which the extracting chamber is in the form of a series of funnels. Fig. 4. shows a detail sectional view of an alternative form of a portion of the device. Fig. 5. shows an end elevation of Fig. 4. 85

As shown in Figs. 1 and 2 of the drawings, we find it desirable to support the periphery of the mill 1 on a series of rollers 2 instead of on a central axis. With such an arrangement the central hollow trunnions can be dispensed with altogether and we may form the ends or part of the ends of the mill of stationary disks 3 of suitable material, said disks supporting the chute 17 and the air inlet tube 4 and outlet conduit 5 for the powdered material ground in the mill above the center of the mill and consequently allowing of the mill being loaded above its center of gravity and thus increasing its output. As shown in 90 Figs. 1 and 2 we may arrange the extracting chamber in the form of a narrow box 6 arranged either at an angle as shown or in an upright or approximately upright position in the mill and extending throughout 95 its length. The top of said chamber is open to receive the powder extracted in the mill and the outlet from said chamber leads to the outlet conduit 5 through the hollow trunnion. At a suitable height above the 100 105 110

chamber 6 we arrange a hood 7 adapted to prevent the entrance of any large particles which may be carried to the upper part of the mill during its rotation. We prefer to provide the box chamber with telescopic sections, such as 8, so that when desired the position of the top of said chamber with regard to the central axis of the mill can be adjusted in order that the consistency of the powder extracted can be graded conveniently. In order to allow of a convenient adjustment of the telescopic sections 8 of the chamber 6 and to insert the pebbles or balls we may arrange a manhole 9 in a convenient position on the periphery of said mill through which the said telescopic sections can be conveniently adjusted. The set screws 10 are provided by which the sections 8 of the chamber 6 can be locked in the desired position. The mill may, if desired be made in two parts (not shown) so that it can be easily taken to pieces and each end may be made removable. If compressed air is used by discharging the powder from the mill through the outlet conduit 5 we provide in the inlet pipe 4 a series of openings 11 adapted to direct a series of jets of compressed air upon the balls or pebbles 12 at right angles to the general level of the material during the rotation of the mill, as shown by the arrows in Fig. 2, in this manner preventing the powder from collecting on the surface of said pebbles and thus causing cushioned surfaces thereon which destroy their grinding efficiency. In the mills of this class in which compressed air has been used the air has been directed from a single jet at one end of the mill to sweep across the pebbles and to pass out at the other end of the mill. The material to be ground is fed into the mill through the chute 17 provided with a series of outlet passages 18 through which there is a constant feed to the mill during its rotation while any material remains in the chamber 17. The powder suspended in the mill during its rotation passes under the hood 7 into the chamber 6 and from thence to the outlet conduit 5, as shown, by the arrows in Figs. 1 and 2. Means may also be provided, such as sliding valves, whereby the size of the inlet passages 18 can be adjusted so as to vary the volume of material fed to the mill, according to the speed at which the mill is rotated and the nature of the material to be ground.

In the alternative form of our invention illustrated in Fig. 3, we arrange in the mill a central pipe 13 leading to the outlet conduit 5 and mount on said passage a series of funnels 14 with curved telescoping ends, conveniently turned alternately in opposite directions, as shown, the pipe 13 and branches 14 constituting the extraction chamber. The powder suspended in the air

during the rotation of the mill passes through the openings 15, 15^a (as shown by the arrows) of said curved ends, while any large particles which may be carried to the top of the mill are prevented from entering by the arched top walls 16 which constitute the hood over the inlet openings. 70

In Figs. 4 and 5 we show another form of a detail portion of our invention in which we provide means whereby the inlet conduits to the mill and the outlet conduit from the extracting chamber are supported by a stationary disk of convenient diameter arranged in one end of the mill, the other end of the mill being attached to and adapted to rotate with the periphery of the mill. The edge 20 of the circular opening formed in the rotating end of the mill which receives the stationary disk 21, is provided with an outwardly extending flange 22 on the internal surface of which is arranged a worm 23. The said disk 21 is provided with a corresponding outwardly extending flange 24. The said worm 23 is adapted to feed back into the mill any dust which may pass from said mill into the joint formed by said surface 20 and the periphery of the disk 21. We arrange a hollow ring 25 adapted to cover the outer end of the joint between said stationary disk 21 and the rotating end of the mill. Compressed air is led into said hollow ring 25 through a passage 26 and this compressed air acts in addition to said worm 23 and returns to the mill any dust which may accumulate in the joint. The air pressure in the ring is higher than the pressure in the mill. In some cases we may find it desirable to dispense with the worm 23 and rely upon compressed air alone to return the dust to the mill. The ring 25 is retained in position by a series of springs 27 arranged between the outer face of said ring and the inner faces of the arms 28 of a standard 29. It will be obvious instead of the arms 28 the upper part of the standard 29 may be in the form of a disk. The stationary disk 21 is conveniently attached to said standard 29 by means of the connecting rod 30. In this arrangement the extracting chamber 6 is supported by said stationary disk 21 conveniently by its outlet conduit 32 which passes through said disk and forms a return pipe parallel with or approximately parallel with the inlet conduit 33 for the chute and the inlet tube 34 leading compressed air into the mill to blow upon the pebbles or balls as previously described. In this arrangement of the mill we may open the chute or inlet conduit 33 for the material to be fed into the mill, to the source of compressed air thus enabling the use of compressed air for feeding the material from the chute into the mill. The arrangement of the inlet for com- 130

pressed air in the chute is a usual and convenient one in mills of this class in which compressed air is used for separating the dust ground in the mill.

5 It is obvious that the extracting chamber shown in Figs. 1 and 2, or that shown in Fig. 3, may be substituted for the arrangement illustrated in Fig. 4. It is also to be understood that the extracting chamber 10 shown in Fig. 4 may be provided with a hood and telescopic walls in the same manner as illustrated in Fig. 2.

15 Although we have described as means for withdrawing the powder ground in the mill the use of compressed air or suction it must be understood that if desired we can arrange a mechanical feed beneath the chamber 6.

What we claim is—

20 1. In a ball or pebble mill the combination of a mill chamber, an inlet conduit for the material to be ground, an internal extracting chamber having an upper inlet opening, a hood covering said inlet opening to said extracting chamber, and adapted to prevent the entrance of any large particles which may be carried to the top of said extracting chamber, said hood and the walls of said extracting chamber being 25 relatively adjustable, and an outlet conduit leading from said extracting chamber for the powder extracted.

25 2. In a ball or pebble mill the combination of a mill chamber, an inlet conduit for the material to be ground, an internal extracting chamber having an inlet opening affording communication between said extracting chamber and the mill chamber, means for adjusting the walls of said 30 chamber to vary the position of said inlet opening in relation to the level of the material in said mill chamber, a hood covering said inlet opening to said extracting chamber adapted to prevent the entrance of any 35 large particles which may be carried to the top of said extracting chamber, and an outlet conduit leading from said extracting chamber for the powder extracted.

30 3. In a ball or pebble mill the combination of a mill chamber, an inlet conduit for the material to be ground, an internal extracting chamber having telescoping walls provided with an inlet opening affording communication with said extracting chamber and the mill chamber, a hood covering said inlet opening to said extracting chamber adapted to prevent the entrance of any large particles which may be carried to the top of said extracting chamber, and an outlet conduit 35 leading from said extracting chamber for the powder extracted.

35 4. In a ball or pebble mill the combination of a mill chamber, an inlet conduit for the material to be ground, a compressed air inlet pipe in parallel relation with said material

inlet conduit having a series of openings in said pipe adapted to direct compressed air upon the balls or pebbles at right angles to the general level of the material during the rotation of the mill, an internal extracting chamber, and an outlet conduit leading from said extracting chamber for the powder extracted.

5. In a ball or pebble mill the combination of a mill chamber, an inlet conduit for the material to be ground, a compressed air inlet pipe extending in parallel relation with said material inlet conduit having a series of openings in said pipe arranged at intervals across the mill chamber and adapted to direct compressed air upon the balls or pebbles at right angles to the general level of the material during the rotation of the mill; an internal extracting chamber having an inlet opening affording communication between said extracting chamber and the mill chamber, a hood covering said inlet opening to said extracting chamber and adapted to prevent the entrance of any large particles which may be carried to the top of said extracting chamber, and an outlet conduit leading from said extracting chamber for the powder extracted.

6. In a ball or pebble mill the combination of a cylindrical mill chamber mounted on a series of rollers, a stationary end to said mill chamber, an inlet conduit for the material to be ground mounted in said stationary end above the axis of rotation of the mill, an internal extracting chamber having an inlet opening affording communication between said extracting chamber and the mill chamber, and an outlet conduit leading from said extracting chamber for the powder extracted.

7. In a ball or pebble mill the combination of a cylindrical mill chamber mounted on a series of rollers, a stationary end to said mill chamber, an inlet conduit for the material to be ground mounted in said stationary end above the axis of rotation of the mill chamber, an internal extracting chamber having an inlet opening affording communication between said extracting chamber and the mill chamber, means for adjusting the walls of said chamber to vary the position of said inlet opening in relation to the level of the material in said mill chamber, and an outlet conduit leading from said extracting chamber for the powder to be extracted.

8. In a ball or pebble mill the combination of a cylindrical mill chamber mounted on a series of rollers, a stationary end to said mill chamber, an inlet conduit for the material to be ground mounted in said stationary end above the axis of rotation of the mill chamber, an internal extracting chamber having telescoping walls and provided with an inlet opening affording communication between said extracting chamber and the mill chamber.

ber, a hood covering said inlet opening to said extracting chamber and adapted to prevent the entrance of any large particles which may be carried to the top of said extracting chamber, and an outlet conduit leading from said extracting chamber for the powder extracted mounted in said stationary end of the mill.

9. In a ball or pebble mill the combination 10 of a cylindrical mill chamber mounted on a series of rollers and having a flange surrounding a circular opening in the end wall of the mill chamber, a worm on the inner periphery of said flange surrounding said 15 circular opening, a stationary disk mounted in said circular opening, an inlet conduit for the material to be ground mounted in said stationary disk, an internal extracting chamber having an inlet opening affording communication between said extracting chamber 20 and the mill chamber, and an outlet conduit leading from said extracting chamber for the powder extracted.

10. In a ball or pebble mill the combination 25 of a cylindrical mill chamber mounted on a series of rollers and having a flange surrounding a circular opening in the end wall of the mill chamber, a worm on the inner periphery of said flange surrounding said 30 circular opening, a stationary disk mounted in said circular opening, an inlet conduit for the material to be ground mounted in said stationary disk, an internal extracting chamber having an inlet opening 35 affording communication between said extracting chamber and the mill chamber, means for adjusting the walls of said chamber to vary the position of said inlet opening in relation to the level of the material in 40 said mill chamber, a hood covering said inlet opening to said extracting chamber adapted to prevent the entrance of any large particles which may be carried to the top of said extracting chamber, and an outlet conduit 45 leading from said extracting chamber for the powder extracted mounted in said stationary disk.

11. In a ball or pebble mill the combination 50 of a cylindrical mill chamber mounted on a series of rollers and having a circular opening in the end wall of the mill chamber, a stationary disk mounted in said circular opening, means for creating a greater fluid pressure than the fluid pressure in the 55 mill chamber on the exterior surface of the joint between said stationary disk and the rotating edge of the end wall of the mill surrounding said circular opening, an inlet conduit for the material to be ground 60 mounted in said stationary disk, an internal

extracting chamber having an inlet opening affording communication between said extracting chamber and the mill chamber, and an outlet conduit leading from said extracting chamber for the powder extracted.

65

12. In a ball or pebble mill the combination of a cylindrical mill chamber mounted on a series of rollers and provided with a circular opening in the end wall of the mill, a stationary disk mounted in said circular opening, a hollow ring adapted to cover the outer end of the joint between the stationary disk and the rotating end of the mill, means for leading compressed air to said hollow ring, an inlet conduit for the material to be ground mounted in said stationary disk, an internal extracting chamber having an inlet opening affording communication between said extracting chamber and the mill chamber, means for adjusting the 70 walls of said extracting chamber to vary the position of said inlet opening in relation to the level of the material in said mill chamber, and an outlet conduit leading from said extracting chamber for the powder to be 75 extracted.

80

13. In a ball or pebble mill the combination of a cylindrical mill chamber mounted on a series of rollers and provided with a circular opening in the end wall of the mill, 90 a stationary disk mounted in said circular opening, a hollow ring adapted to cover the outer end of the joint between the stationary disk and the rotating end of the mill, means for leading compressed air to said hollow ring, a standard, a series of springs arranged between the outer face of said hollow ring and the inner face of said standard, an inlet conduit for the material to be ground mounted in said stationary disk, an internal extracting chamber having telescoping walls and provided with an inlet opening affording communication between said extracting chamber and the mill chamber, a hood covering 95 said inlet opening to said extracting chamber and adapted to prevent the entrance of any large particles which may be carried to the top of said extracting chamber, and an outlet conduit leading from said extracting chamber for the powder to be 100 extracted.
